[57] **CLAIM**

The ornamental design for a heated water dish for pet,
as shown and described.

DESCRIPTION

FIG. 1 is a front elevational view of the heated water dish for pet showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a cross sectional view thereof; and,

FIG. 8 is a perspective view thereof.

The cord is shown broken away in FIGS. 1, 2, 5, and 8
to show indeterminate length.
